UNITED STATES PATENT OFFICE.

JOHN CAMPBELL HODGE, OF CHICAGO, ILLINOIS, ASSIGNOR TO WESTERN ELECTRIC COMPANY, INCORPORATED, OF NEW YORK, N. Y., A CORPORATION OF NEW YORK.

MATERIAL-HANDLING APPARATUS.

Application filed July 31, 1926. Serial No. 128,164.

This invention relates to material handling apparatus, and more particularly to strand twisting or stranding apparatus used in the manufacture of multi-strand cables.

5 The object of this invention is to provide a material handling apparatus wherein the starting and stopping of the various operating parts are controlled in an efficient and economical manner.

10 In accordance with the general features of this invention as applied to a stranding apparatus used in the manufacture of telephone cables, there is provided an interlock mechanism between a capstan and a take-up reel which is operated in a definite sequence to first associate the take-up reel drive mechanism with the main driving element following which the main clutch may be actuated to operatively connect the capstan and the other operating parts of the strander including the take-up reel drive mechanism to the main driving element. Simultaneously with the operation of the clutch to cause the strander to operate, mechanism is actuated for releasing a brake associated with the main driving element, the mechanism also serving to apply the brake to quickly stop the strander upon a reverse operation of the clutch.

15 Other objects and advantages of this invention will more fully appear from the accompanying detailed description taken in connection with the accompanying drawings, in which:

20 Fig. 1 is a fragmentary front view of a telephone cable stranding apparatus embodying the features of this invention;

25 Fig. 2 is a vertical sectional view of the clutch control box;

30 Fig. 3 is a fragmentary section partly in elevation on the line 3-3 thereof;

35 Fig. 4 is a fragmentary section partly in elevation on the line 4-4 of Fig. 2;

40 Figs. 5, 6 and 7 are sections on the line 5-5 of Fig. 3 showing different positions of the inter-control elements;

45 Fig. 8 is a fragmentary sectional plan view of the main clutch;

50 Fig. 9 is a side view of the brake mechanism applied to the driven member of the main clutch;

55 Fig. 10 is an end view thereof partly in section;

60 Fig. 11 is a schematic skeletonized view, partly in section, of the driving mechanism

for the stranding apparatus showing the inter-control mechanism between the capstan and the take-up reel drives and for operating the brake mechanism, and

Fig. 12 is a fragmentary side view thereof. 60

The features of this invention have been shown embodied in a stranding apparatus such as is used in the manufacture of telephone cables, which apparatus being of a well known type has been illustrated in 65 schematic form. The apparatus as far as is material to this invention, consists of one or more similar stranding units 15 (Figs. 1 and 11) each comprising a suitably revolvably journaled drum 16 supporting a 70 plurality of spools of wire (not shown) to be stranded into a cable, the drum carrying at each end a ring gear 17 which is operatively connected to a driving mechanism to be described hereinafter. It is thought a 75 further description of the drum 16 is unnecessary, for a reference may be had to Patent 1,579,769, to H. F. Jones, dated April 6, 1926, for a more detailed description thereof. Attached to the right end of 80 the right unit 15, as viewed in Fig. 1, is a stationary polisher 18 through which wires 19 from the supply spools are drawn in being formed into a cable 20. The wires 19 are withdrawn from their supply spools, 85 drawn through the stranding drum 16 and thence through the above mentioned polisher by a power driven capstan 22, the stranded cable 20 being wound upon a power driven take-up reel 23 carried upon 90 a truck 24.

Intermediate the capstan 22 and the reel 23 is a standard 25 supporting a distributing mechanism 26 for feeding the cable 20 as delivered from the capstan 22 to the rotating 95 reel 23 in such a manner that the cable is coiled thereon in close even spirals. The cable in passing from the capstan to the reel nests upon a traversing arm 28 which is controlled by a device 29 reciprocated by a right and left hand screw 30 whereby the arm is moved upwardly and downwardly to guide the cable to the reel 23. This mechanism is of a well known type and therefore does not require detailed description, as it forms no 100 part of the present invention.

The drum 16, capstan 22, take-up reel 23 and distributing screw 30 are operated from a motor 31 (Fig. 11) in the following manner. Referring particularly to Figs. 8 and 110

11, a shaft 32 is extended from the motor 31 and slidably carried thereon but rotatably fixed thereto as indicated by the spline connection 33 is a driving member 34 of a single plate friction clutch 35. A driven member 38 of the clutch, in addition to forming a housing therefor, provides a circular braking surface 39 which will hereinafter be referred to. Slidably carried upon the shaft 32 and free to rotate thereon, is a sleeve 40 provided with an annular external flange upon its left end (Fig. 8) upon which is similarly mounted a sleeve 41 provided with an annular internal flange formed upon the right end thereof, which in the position shown engages the flange upon the sleeve 40. The sleeve 41 at its left end is formed with a peripheral channel 42 and operatively associated therein is a plurality of equally spaced toggle arms 43, one of which shows in the drawings (Fig. 8). The arms 43 are each pivotally connected to the driven member 38 as indicated at 44 and to a shoe 47 as indicated at 48. The shoes 47 engage inclined faces formed upon a ring shaped friction plate 49. Upon opposite faces of the driving member 34 are rings 50 composed of any suitable friction material which in the engaged position of the clutch as shown in Fig. 8 are in clutching relation with opposite faces of a wall of the driving member 34, the driven member 38 and with the ring 49. To provide a necessary pressure between the friction clutch surfaces a spiral telescopic spring 51 is interposed between a vertical wall formed upon the sleeve 41 and a depression formed in the right end wall of the driven member 38. In the operated position of the clutch as shown in Fig. 8, the spring 51 has expanded and moved the sleeve 41 to the left, rocking the toggle arms 43 in a counter-clockwise direction and thereby causing the shoes 47 to press against the inclined faces upon the friction ring 49 to give a clutching effect between the driving and driven members 34 and 38 respectively through the interposed friction rings 50. The operation of the clutch is effected through the rocking of a yoke 52 secured to a suitably journaled shaft 53, the yoke being provided with diametrically opposed shifting pins 54 positioned in an annular channel formed between the right end of the sleeve 41 and a thrust ball bearing 55 rotatably carried upon the sleeve 40, the bearing 55 being locked thereupon by a nut 56. It will be apparent that upon rocking the yoke 52 clockwise as viewed in Fig. 9, the sleeve 41 will be moved toward the right (Fig. 8) through the cooperating flanges formed upon the sleeves 40 and 41. This movement of the sleeve 41 compresses the spring 51 and rocks the toggle arms 43 clockwise about their pivots 44, thereby releasing the pressure of the shoes 47 upon the friction ring 49 and

consequently causing the disengagement of the clutch driving and driven members.

The operative drive from the driven member 38 of the clutch to the ring gears 17 of the strander drum 16 comprises the following. Referring to Fig. 11, the driven member 38 upon its left end is provided with a sleeve portion 57 to which is secured a sprocket 59 which drives to a line shaft 60 through a chain and sprocket 61, the shaft 60 extending substantially the full length of the stranding apparatus, the purpose of which will be made apparent as this description progresses. Gear pinions 62 carried upon the shaft 60 drive to the ring gears 17 through idler gears 63.

It is desirable upon the disengagement of the clutch, due to the inertia of the rotating stranding apparatus, to apply a braking force thereto to quickly stop the rotation thereof and upon engagement of the clutch to simultaneously release the brake. Referring to Figs. 9 and 10, the shaft 32, the clutch 35 and the associated brake mechanism to be presently described are carried upon a vertical frame 64, the shaft 32 being rotatably journaled in bearings 65 carried upon the upper surface of the frame. Attached to the frame 64 to the left of the driven clutch member 38 is an air cylinder 66 having a piston 67. A rod 68 secured to the piston extends upwardly from the cylinder 66 and is pivotally connected to one end of a lever 69 which is secured to a shaft 70 rotatably journaled in a bracket 71 attached to the frame 64 intermediate the bearings 65. Attached to the opposite end of the shaft 70 is a second lever 72 to the free end of which is secured one end of a brake band 73 comprising a steel band provided with a facing of any suitable friction material which contacts with the braking surface 39 of the driven clutch member 38. The opposite end of the brake band 73 is attached to the lower end of a threaded rod 75 yieldably fixed to a horizontally disposed stationary pin 76, as clearly indicated in the drawings. A tension spring 77, opposite ends of which are attached to the lever 69 and the air cylinder 66, serves to relax the brake band 73 upon the braking surface 39 upon release of the brake mechanism. Disposed at opposite ends of the shaft 53 are levers 78 and 79.

The free end of the lever 79 carries an adjustable pin 82, the engaging end of which is arranged to contact with a valve stem 83 of a valve 84 of any usual and well known type, for controlling the passage of air under pressure from a main air line 85 which may be connected to a suitable supply source (not shown), the valve being carried upon a bracket 86. The outlet end of the valve 84 is connected to the lower end of the air cylinder 66 by an air line 89. The

lever 78 at its lower end is pivotally connected to a lever and link mechanism to be described in detail hereinafter. As hereinbefore mentioned, the clutch members are 5 shown in an engaged position, consequently the braking mechanism at this time is inoperative. This condition of the latter mechanism is indicated in the drawings by the gap between the outer ends of the valve 10 stem 83 and the pin 82, a spring (not shown) may be provided to insure the closing of the valve, although the pressure of the air in the valve is generally sufficient for this purpose. As hereinbefore described, the 15 clutch is disengaged by rocking the yoke 52 clockwise which operation is accomplished by a movement of the lower end of the lever 78 toward the left as viewed in Figs. 9 and 12. The pin 82 upon the lever 20 79 thus engages the valve stem 83 and against the action of the spring (not shown) opens the valve 84 thereby causing the braking mechanism hereinbefore described to be actuated and thus quickly stopping 25 the rotation of the stranding apparatus.

Referring to Fig. 11 power is transmitted from the line shaft 60 to the capstan 22 for operating the latter at the desired speed and direction by gearing 90. The right 30 and left hand distributing screw shaft 30 and the take-up reel 23 are also operated from the line shaft 60 in the following manner. The shaft 60 has fixed thereto at its extreme right end a sprocket 91, which 35 drives through a chain 92 to a sprocket 93, which as clearly shown in Fig. 12 is positioned therebelow, the chain extending upwardly through an opening provided in the floor. The sprocket 93 is secured to a stub 40 shaft 94 which through a pinion 96 attached thereto and suitable gearing 97 furnishes motion to the distributing screw shaft 30. At its extreme right end the shaft 94 carries a worm 98 which meshes with a worm 45 wheel 99, the latter being splined to a vertical shaft 100 as indicated at 101. Fixed to the upper end of the shaft 100 is a jaw clutch member 104. Attached to the shaft 100 intermediate the worm wheel 99 and 50 the member 104 is a collar 105 provided with an open annular channel and extending thereinto at diametrically opposite points are pins 106 secured to the bifurcated ends of a yoke member 107. In the 55 inoperative position of the clutch member 104 the upper surface thereof lies substantially flush with the floor line but in its clutched position as shown in Figs. 1 and 12 it has been moved upwardly through 60 actuation of the yoke member 107, the operation of which will be presently described, and into clutching relationship with a clutch member 108 secured to a shaft 111 journaled upon the reel truck 24, the spline 101 permitting the upward movement of the shaft

100. The reel 23 is suitably attached for rotation with the shaft 100 which has been centered with respect to the clutch member 104. To facilitate the centering of the truck 24 and retaining it in position there 70 are provided guide strips 112 secured to the floor and a centering pin 113 carried upon an arm 114 adjustably mounted for vertical movement upon the standard 25, the pin 113 being arranged to enter a socket (not 75 shown) provided in the upper end of the reel 23 and in axial alignment with the shaft 111 (Fig. 1). From the above description it will be apparent upon closing the main clutch 35 in the manner hereinbefore described, the motor 31 having been previously caused to operate, that the one or more strander units 15, the capstan 22, the distributor shaft 30 and the take-up 80 reel 23 will all operate in unison. 85

The means for operatively engaging the take-up reel clutch members 104 and 108 and the members 34 and 38 of the main drive clutch 35 in a predetermined definite sequence comprises the following lever and 90 link mechanism.

Disposed between the capstan 22 and the distributing mechanism 26 and mounted upon the floor at a convenient operating point (Fig. 1) is a housing 116 which supports the take-up reel and main clutch operating hand levers 117 and 118 respectively and houses an inter-control mechanism associated therebetween. The levers 117 and 118 are shown in their operated positions, 95 their associated clutches as hereinbefore described being shown in operative condition. The levers 117 and 118 are pivoted upon a rod 119 mounted upon the upper portion of the housing and are adapted to be separately retained in an operated position (Fig. 2) or tripped therefrom by detent and tripping devices 120 individual to each, the inoperative position of the levers being indicated in dotted outline. The lever 117 intermediate its pivotal point and the handle portion thereof is connected to a depending link rod 123 connected at its lower end to an arm 124 in turn attached to one end of a rock sleeve 125 which carries at its opposite extremity an arm 126 (Figs. 11 and 12), the rock sleeve 125 being journaled upon a rock shaft 127. The rock shaft 127, as will be more fully described hereinafter, 100 controls the operation of the main clutch 35 through the actuation of the yoke 52. The arm 126 is connected to one arm of a bell crank lever 130 by a link rod 131, the lever 130 being journaled upon a bracket (not shown) mounted upon the floor. The other arm of the bell crank lever 130 is connected to one end of a depending link rod 132 which extends through an opening in the floor; the opposite extremity of the rod 132 being connected to one end of a lever 133. 105 110 115 120 125 130

which is attached to one end of a rock shaft 134 carrying at its opposite end the yoke member 107.

The means for transmitting motion from the rock shaft 127 to the yoke 52 which controls the main clutch 35 will now be described. The lever 118 at its left end (Fig. 2) is connected to a depending link rod 137 connected at its lower extremity to an arm 10 138 attached to one end of the rock shaft 127. An arm 139 (Figs. 11 and 12) fixed to the shaft 127 at the opposite end is connected to the lower arm of a lever 140 journaled upon a bracket (not shown) mounted upon the 15 floor through a link rod 142, the upper arm of the lever 140 being connected to the lower extremity of the lever 78 by a link rod 143. The leverage of the motion transmitting means just described connected to the 20 hand levers 117 and 118 at one end and to the clutch yokes 107 and 52 respectively at their opposite ends is such that upon movement of the levers from their normal position (dotted outline Fig. 2) to their operated 25 position shown in full lines the take-up reel and main drive clutches will be engaged in the manner hereinbefore described and upon a reverse movement disengaged.

Referring now to Figs. 3, 5, 6 and 7, it 30 will be noted that the levers 117 and 118 are provided with coaxial bearing or sleeve portions 146 and 147 respectively which in the movement of the levers rotate upon the rod 119. The inner abutting end faces of the 35 sleeve portions 146 and 147 are provided with interlocking jaws 148 and 149 respectively, the gaps between the jaws of each sleeve portion being wider than the jaws. In Fig. 5, is illustrated the relative position of the interlocking jaws 148 and 149 with the levers 40 in their normal position, the stranding apparatus being idle while Fig. 7 shows the relative position of the parts with the take-up reel and main drive clutches engaged. 45 With this interlocking construction an operator cannot move the main drive clutch operating lever 118 clockwise from its normal position (dotted outline Fig. 2) to its operated position without first engaging the 50 take-up reel clutch, as hereinbefore described, and which is accomplished by moving the lever clockwise from its dotted outline position (Fig. 2) to the full line position thereof. This will be readily apparent by referring to Fig. 5 wherein it will be noted that no 55 gap occurs between the adjacent sides of the jaws 149 and 148 which will permit the jaws 149 integral with the lever 118 to move clockwise but a gap 150 does occur between the 60 opposite adjacent sides of the jaws. Thus when the apparatus is ready for the stranding operation the operator first grasps the lever 117, trips the detent mechanism 120 and presses down upon the lever which ro-

tates the jaws 148 clockwise thereby closing 65 the gaps 150 and forming similar gaps 151 between the opposite sides of the jaws (Fig. 6). Thereafter the lever 118 may be manipulated in a similar manner thus rotating the jaws 149 clockwise and closing the gaps 70 151 and through the associated leverage system closing the main drive clutch 35. The last position of the interlocking elements is clearly illustrated in Fig. 7. When stopping 75 the stranding apparatus the main drive clutch 35 can only be opened by operating the levers 117 and 118 in reverse order to that just described for starting the apparatus.

It is evident that with this invention the 80 rotary drums 16 together with the capstan 22 which serves to draw the wires 19 therefrom for forming the cable 20 cannot be set in motion without first completing an operative connection between the then idle driving mechanism and the take-up reel 23, thus providing against loss of time and possible damage to the cable 20. Also upon completion of the stranding operation the main 85 drive clutch 35 has to be first disengaged 90 before the take-up reel clutch member 104 can be disengaged from the clutch member 108 carried by the take-up reel 23 thereby preventing damage, likely to occur, if the driving and driven members 104 and 108 95 respectively were disengaged during motion of the driven member 104 through the engagement of the clutch 35.

From the description hereinbefore given 100 of the brake mechanism associated with the driven member 38 of the clutch 35 and the actuating means therefor, it will be evident that upon movement of the clutch operating lever 118 from its normal position to its 105 operated position and vice versa the lever 79 carried by the shaft 53 will be simultaneously rocked to operate the valve 84, thereby releasing and applying the brake upon starting and stopping the stranding apparatus respectively.

What is claimed is:

1. In a strand working apparatus, strand working means, means for receiving worked strand therefrom, driving means for the working means, a driving connection from the driving means to the receiving means, and individual controlling means for the driving means and the driving connection from the driving means to the receiving means, each acting in one position to control the actuation of the other.

2. In a strand working apparatus, strand working means, means for receiving worked strand therefrom, driving means for the working means, a driving connection including a clutch device between the driving means and the receiving means, and individual interlocking controlling means for the driving

means and the clutch device for limiting the actuation of the latter means to a predetermined sequence.

3. In a strand working apparatus, strand working means, means for receiving worked strand therefrom, driving means for the working means, a driving connection from the driving means to the receiving means, individual clutch devices for connecting the driving means to the working means and the driving connection from the driving means to the receiving means, and individual controlling means for the individual clutch devices, each acting in one position to control the actuation of the other.

4. In a strand working apparatus, strand working means, means for receiving worked strand therefrom, driving means for the working means, a driving connection from the driving means to the receiving means, individual means for forming an operative connection between the working and driving means and between the driving connection and the receiving means, and manually actu-

ated individual members for controlling the individual means, the members having interlocking axial portions for limiting their actuation to a predetermined sequence.

5. In a strand working apparatus, strand working means, means for receiving worked strand therefrom, driving means for the working means, a driving connection from the driving means to the receiving means, individual means for forming an operative connection between the working and driving means and between the driving connection and the receiving means, and coaxially mounted manually actuated levers for controlling the individual means, the levers being provided upon axial aligned parallel faces with interlocking jaws with the gaps between the jaws of each face being wider than the jaws for limiting the actuation of the levers to a predetermined sequence.

In witness whereof, I hereunto subscribe my name this 24 day of July A. D., 1926.

JOHN CAMPBELL HODGE.
